Sam'l D. Vose of Albany N. Y.
Letters Patent No 463 Dated June 22nd 1852

The schedule referred to in these Letters Patent and making part of the same

To all whom it may concern:

Be it known that I Sam'l D. Vose of Albany County of Albany and state of New York have invented or produced a new ornamental design for a Coal Burner Stove and I do hereby declare the following is a full and exact description of the same reference being had to the annexed drawings affixed to and making part of this specification.

Fig 1 Represents the coal burner (perspectively)

Fig 2 " " ends

Fig 3 " " back

U represents the iron

T " " top

F " " front

B " " Base

1 " legs

My invention consists in the combination of the several mouldings and ornaments as arranged in the whole stove, and is not easily described in words and reference is therefore made to the drawings.

I do not claim any detailed part of the mouldings or configuration.

What I claim as my invention and desire to secure by Letters Patent is the combination of the several mouldings and ornaments as arranged together the whole forming an ornamental design for a Coal Burner Stove as herein set forth and described.
